ARTICULATED ORNAMENTAL COVERING
FOR FLEXIBLE APPAREL ACCESSORIES

Jacob Kaplan, Bronx, N. Y.

Application August 10, 1945, Serial No. 610,102

5 Claims. (Cl. 41—10)

1

This invention relates to articulated surfaces such as are employed for the ornamental covering of flexible apparel accessories, like handbags, belts, etc.

More particularly, the invention is concerned with an articulated surface comprising a plurality of rigid molded plaques which are hinged together in such manner that any plaque can be swung to a limited extent relative to all adjoining plaques. The plaques are hollow and open at the rear, preferably being made of a plastic, i. e., any one of a large group of natural and synthetic organic materials derived from cellulose, proteins, hydrocarbons, or resins, which are moldable under heat or heat and pressure. Examples of plastics are cellulose acetate, cellulose acetate butyrate, ethyl cellulose, vinyl acetal resins, vinyl ester resins, acrylic resins, styrene resins, urea resins and phenolic resins.

At the present time, commercial articulated surfaces of the character described comprise plaques which are hinged together by transverse sets of laces, and are constructed in either one of two fashions. In one type of articulated surface, the laces are threaded through registered laterally extending apertures which run vertically from the top to the bottom surface of the plaques. This kind of plaque has the advantage that a simple two-part die can mold the same, complete with its threading apertures, in one operation. However, such articulated surfaces expose the laces, thus allowing them to become dirty and frayed.

In the other type of articulated surface, the threading apertures are holes which run laterally through vertical, rearwardly extending peripheral walls of the plaques. This plaque has the advantage of concealing the laces, but it cannot be molded in a two-part die in one operation. Such plaques either require dies consisting of three or more relatively movable parts, or the threading apertures must be made after the plaque is molded.

It is a primary object of my invention to provide plaques of the character described which, like present-day plaques, can be laced together but in which the threading apertures are so located that the laces are barely visible and which are so constructed that they can be molded in one operation by a simple two-part die.

It is another object of my invention to provide an articulated surface of the character described which is very flexible both forwardly and reversely.

It is a further object of my invention to provide sturdy plaques which can be laced together in a simple and inexpensive manner.

2

An additional object of my invention is to provide an articulated surface having plaques hinged together by a single series of non-intersecting laces, as distinguished from the transverse series of laces heretofore employed.

Still another object of my invention is to provide a handbag covered with an articulated surface having oblique articulated hollow corners.

Yet another object of my invention is to provide an articulated surface of the character described which shall be economical to manufacture and durable in use.

Other objects of the invention will in part be obvious and in part hereinafter pointed out.

The invention, accordingly, consists of the features of construction, combinations of elements and arrangements of parts which will be exemplified in the constructions hereinafter described, and of which the scope of application will be indicated in the appended claims.

In the accompanying drawings, in which are shown various possible embodiments of my invention,

Fig. 1 is a sectional view through a two-part die having a mold cavity adapted to form a plaque embodying my invention;

Fig. 2 is a top plan view of a plaque made in the die shown in Fig. 1;

Fig. 3 is an edge view of said plaque;

Figs. 4 and 5 are sectional views through said plaque, taken substantially along the lines 4—4 and 5—5, respectively, of Fig. 2;

Fig. 6 is a perspective view of a corner of a plaque embodying a modified form of my invention, wherein a lace is adapted to be slipped sideways into a threading aperture;

Fig. 7 is a fragmentary rear view of an articulated surface embodying my invention, different types of lacing being illustrated in different parts of said surface;

Fig. 8 is a front view of an articulated surface embodying my invention and so constructed that it is adapted to form a handbag covering having peaked side edges and a flat bottom edge;

Fig. 9 is a perspective view of a handbag covered with the articulated surface shown in Fig. 8;

Fig. 10 is a fragmentary sectional view taken substantially along the line 10—10 of Fig. 9, the interior portions of the lacing being omitted so that the relative disposition of the plaques can be seen more clearly;

Fig. 11 is a fragmentary top plan view of the handbag shown in Fig. 9;

Fig. 12 is a sectional view through said handbag, taken substantially along the lines 12—12 of Fig. 11, the interior lacing being omitted for the reason above mentioned;

Fig. 13 is a view similar to Fig. 8 of an articulated surface adapted to form a handbag covering having peaked side and bottom edges;

Figs. 14 and 15 are side and front views, respectively, of the bottom corner of a handbag covered with the articulated surface shown in Fig. 13;

Fig. 16 is a sectional view similar to Fig. 10 but taken substantially along the lines 16-16 of Fig. 15;

Fig. 17 is a fragmentary perspective view including the bottom corner of a handbag covered with an articulated surface embodying another modified form of my invention; and

Fig. 18 is a similar view of a handbag embodying still another form of my invention.

In general, I attain the objects of my invention relating to the plaques, by providing a plaque having a rearwardly extending peripheral rim with through slots in its bottom edge located in the registered positions at which the threading apertures are to be disposed. The outer side of each slot near its open bottom end is bridged by a projection integral with and extending outwardly from said rim adjacent its bottom edge. Each slot and projection cooperate to define a threading aperture extending from the bottom surface of the plaque to the outer side surface of the rim. Thus, registered pairs of threading apertures, because they do not run to the top surfaces of the plaques, can be located very close to each other (double the distance a projection extends from the rim), thereby preventing substantial exposure of the laces. At the same time, however, due to the peculiar formation of the threading apertures, the plaques can be cast in a simple two-part mold in one operation.

Furthermore, if desired, lacing may be expedited by forming slots in the ledge, each offset from the center of and running into a threading aperture, so that a lace may be slipped into each aperture instead of having to be inserted end-most therethrough.

With respect to the lacing, the basic novelty of the invention consists in hingedly joining the plaques with rows of laces which do not intersect but, nevertheless, permit flexure of the articulated surface about transverse axes. To obtain such a desirable result, the plaques are made in a polygonal shape and each side is provided with two threading apertures instead of the one now commonly employed. These threading apertures are disposed adjacent the ends of the sides, i. e., at the corners of the plaques, and the apertures in adjacent plaques are registered. Each line or row of lacing hingedly joins together the plaques in two rows, instead of one as heretofore, by passing through one after another sets of adjacent registered threading apertures around every place in the two rows of plaques where the corners of several plaques meet at a common point. Thus, at every such point a plaque in one row is hingedly joined to one or more plaques in the same row as well as to one or more plaques in the adjoining row, and, in this way, the need for a transverse set of laces is obviated.

The object of my invention concerning the hollow oblique articulated corners of a handbag is achieved by utilizing a few triangular plaques of the proper size and angularity in conjunction with quadrilateral plaques in the main body of the articulated surface. By differently arranging these two types of plaques, a large variety of variously shaped corners can be obtained, this be-

ing a marked improvement over present-day handbags, in which the corners of the bags are either not hollow, or, if hollow, are orthogonal.

Referring now in detail to the drawings and, more particularly to Figs. 2-5, I have there shown a plaque 20 embodying my invention and adapted to form one element of an articulated surface. Said plaque comprises a rectangular top wall 22 having rearwardly extending peripheral walls 24 comprising front and back walls 24 and side walls 26. A flange or ledge 28 integrally projects a short distance from the bottom edges of the front, back and side walls, said ledge extending parallel to the top wall 22. Although for purposes of illustration I have shown the top wall as rectangular, it will be understood that such shape may be modified in any suitable fashion. Thus, by way of example, said wall may be square, triangular, hexangular or circular. In order to minimize exposure of the laces which hingedly connect the plaques, the rearwardly extending peripheral walls are vertical, i. e., perpendicular to the plane defined by all the top walls in an articulated surface when the same is unflexed, it being understood that the peripheral walls may have a conventional draft to facilitate removal of the plaques from a mold.

The top wall 22, instead of being flat as shown, may be concave or convex or of any other desired contour. It is particularly emphasized, however, that if the edges of the top wall are inclined, such edges form no part of the vertical peripheral walls.

A plaque, such as just described, has a hollow interior which opens at the rear. Said plaque 20 is made from any suitable moldable material, plastics being preferred because of their lightness and ease of molding.

Pursuant to my invention, I provide threading apertures 30 in the vertical peripheral walls 24, 26. Each of these apertures comprises a slot 32 which extends laterally through the wall in which it is disposed and runs up from the bottom edge of said wall to above the top of the ledge 28. The ledge 28 bridges a portion of the slot adjacent its open bottom end, and, with the slot defines the threading aperture. A slot of this nature can be molded by a fixed projection in that part of the mold which imparts the desired configuration to the bottom surface of the plaque, yet the resulting threading aperture 30 is not exposed on the top surface of the plaque, so that the threading apertures can be placed close together, if desired.

The space between the peripheral walls of adjacent plaques, and thus the extent to which the lacing is exposed, is determined by the width of the ledges 28, and said ledges, therefore, may be made as narrow as is consistent with strength. Said ledges, in addition to functioning as an edge of each threading aperture, reinforce the peripheral walls of the plaque and thus provide the plaques with a greater inherent strength than that of those now sold commercially.

If desired, the slots 32 may extend a slight distance into the ledge 28, it being noted that the opening 34 thus created will be substantially concealed by the lacing. However, in general, it is desirable to minimize the depth of the opening 34.

In accordance with an ancillary feature of my invention, I may provide means associated with each threading aperture to expedite the threading of a lacing cord or tape therethrough. Such means, as illustrated, comprises a track 36 includ-

ing two spaced parallel ribs 38, defining an open channel leading up to the aperture 30. Said channel is molded in the top wall 22, and the base 40 of the channel adjacent the aperture is substantially of the same shape as the matching part of said aperture, so that the end of a cord pushed along the channel will be guided into the threading aperture. The outer ends of the ribs 38 may be flared to facilitate insertion of the end of the cord in the track.

In Fig. 1, I have shown a two-part molding die 42, adapted to form a plaque 20, such as just described. Said die consists of two parts 44, 46, the lower of which has a plurality of projections 48 for making the slots 32.

The formation of the threading apertures 30 may be altered somewhat, as indicated in Fig. 6, to expedite threading of the laces in such manner that the laces can be slipped edgewise into said apertures rather than be inserted endmost therethrough.

As shown in said figure, the plaque 20' includes threading apertures 30' which are formed in the same manner as the apertures 30, i. e., each such aperture comprises a slot 32' extending through the peripheral wall 24' and running up from the bottom of said wall to above the top of the ledge 28'. However, in said plaque 20' a second slot 50 is provided, which is disposed immediately alongside the slot 32' and is in communication therewith at 52. The slot 50 extends through the ledge 28' and the peripheral wall 24', but need not be as deep as the slot 32'.

The two slots 32' and 50 combine to form a bayonet or L-shaped opening, of which the slot 50 comprises the entry portion and the part of the slot 32' bridged by the ledge 28' comprises the locking portion, in which the lace is disposed after the same is slipped edgewise through the entry slot 50. The portion 52, common to both slots 32' and 50, may be somewhat constricted, i. e., smaller in diameter than either of the slots 32', 50, so that the lace, when passing from the entry to the locking portion of the bayonet opening, has to be squeezed through the portion 52 and thus will tend to remain in the threading aperture 30'. Furthermore, for a reason which will be soon apparent, I prefer to dispose the entry slots 50 further from the corner than the slots 32', when a system of lacing embodying a feature of my invention, hereinafter described, is employed to articulatedly join the plaques 20'.

The plaques are arranged in edge-to-edge abutting relationship and in transverse horizontal and vertical linear alignment, as indicated in Fig. 7, and are laced together in such position. For this purpose any conventional transverse series of lacing cords or tapes may be employed in a manner well known to the art. However, pursuant to a feature of my invention, I secure the several plaques together in articulated relationship by employing a single non-intersecting series of laces, thus saving material and expediting the joining of the plaques.

Basically, this novel system of lacing is effected by passing a cord or tape through a series of pairs of registered apertures in the side walls of all of the plaques meeting at a common point, these apertures being disposed near said point and the number of sets of apertures being at least equal to or no fewer than one less than the number of plaques meeting at such point. In other words, if four plaques meet at a point, as is the case where the plaques are quadrilateral, then a lace is threaded through at least three pairs of regis-

tered apertures in the side walls of said plaques adjacent the common point. The cord will thus pass through a side wall of at least every one of the four plaques near the common point they all surround and each such plaque can move hingedly with respect to the other three.

For convenience, that portion of the lace which is passed through the pairs of registered apertures disposed around a common point will be referred to hereinafter as a "lacing ring." A system of lacing which includes such rings is susceptible of many modifications and in Fig. 7 I have shown four such modifications. All of these modifications are illustrated on one articulated surface. However, it is to be understood that any one of the different systems of lacing might be used to hingedly connect all the plaques in an articulated surface, or, if desired, two or more such systems might be employed in a single articulated surface.

Referring now to the extreme left-hand side of Fig. 7, I have there shown a cord 54 employed to lace together a pair 56 of vertical rows of plaques. Said cord is first passed through the top pair *a* of the registered threading apertures 30 in the side walls 26 of the uppermost pair of juxtaposed plaques A, B, and then through the bottom pair *b* of apertures in said walls. Next, the cord is passed through the pair *c* of registered threading apertures in the juxtaposed front and back walls of the plaques A, C, this set of apertures being those nearest the point I, where the plaques A, B, C and D meet. Now the thread is passed through the pair *a* of registered threading apertures in the plaques C, D.

That portion of the cord which passes counter-clockwise through the last three mentioned sets of registered threading apertures *b*, *c* and *a* comprises a lacing ring.

The thread now continues downwardly through the remaining plaques of the pair 56 of vertical rows, the threading operations being repeated. Knots 58 are tied at both ends of the cord immediately adjacent the threading apertures 30 from which the free ends of the cord extend. The cord should be drawn tight before these knots are tied, so that there will be very little play between adjacent plaques. It will be noted that drawing the cord tight forces the same towards the corners of the plaques, and, if bayonet apertures are employed, this prevents the cord from slipping out of the entry portions of slots which are further from the corner than the locking portions.

These two vertical rows of plaques now can be articulated either about a horizontal or vertical axis in either a forward or reverse direction. A "forward" direction denotes that the rear of the articulated surface is made concave and a "reverse" direction indicates that the rear of the articulated surface is made convex.

It is pointed out that, where the lacing ring extends through only three sets of registered apertures, as indicated in the pair 56 of rows, the front of the articulated surface will show tiny portions of the cord at only three places around a common point I, two of the portions being spaced apart 180° from one another and the remaining portions 90°.

Attention is also called to the fact that transverse articulation is attained by this system of lacing, with the use of non-intersecting cords or tapes, since at each common point I a lacing ring hingedly secures together all plaques surrounding said point, whereas, when transverse

sets of laces are employed, each lace only hingedly connects together plaques along a line. It will be observed further that the specific system of lacing just described leaves the outer edges of adjacent plaques unattached. This is satisfactory if such edges are either fastened to the bag fabric or are laced to another row of plaques at the opposite side, end or bottom of the handbag. However, if it is desired to secure together these free edges of the plaques, it is only necessary to run a cord 60 through the registered pairs *d* of threading apertures at the left-hand side of the juxtaposed front and back walls of the plaques A, C, etc., as indicated. Instead of tying knots in the ends of the cords, one or both ends may be anchored by three pins 61, depending from the under surface of the top wall. These pins are spaced apart a distance less than the thickness of the cord 60. To secure an end of the cord, the same is squeezed between two pins 61, bent back on the center pin and then squeezed through between the center and remaining pin.

At the right of the pair 56 of rows I have shown another pair 62 of vertical rows of plaques, laced together in a slightly different fashion which also includes the use of lacing rings. The cord 64, used to secure the rows 62 of plaques together, passes through the pairs of registered apertures in the following manner: *a* (between plaques F and E); *c* (between plaques E and G); *a* (between plaques G and H); *d* (between plaques H and F); *b* (between plaques F and E); *d* (between plaques E and G); *c* (between plaques G and J); *a* (between plaques J and K); etc. If the cords 54 and 64 are immediately adjacent, the right-hand row of plaques in the rows 56 will be the same as the left-hand row of plaques in the rows 62, i. e., the plaques B and E will be the same, the plaques D and G will be the same, etc.

Still another threading system is shown in the pair 66 of rows to the right of the pair 62 of rows. In this case the threading order of the cord 68 is clockwise in the lacing rings and is as follows: *a* (between plaques M and L); *b* (between plaques L and M); *d* (between plaques M and O); *a* (between plaques O and N); *b* (between plaques N and O); etc., to the bottom of the pair 66 of rows, returning through the pairs *c* of apertures and finishing with the pair *c* of apertures between the plaques N and L.

At the extreme right-hand side of Fig. 7, I have shown yet another system of lacing, wherein the pairs 70 of rows of plaques are laced together by a cord 72, which passes through the threading apertures in the following order: *a* (between plaques P and Q); *b* (between plaques Q and P); *c* (between plaques P and R); *a* (between plaques R and S); *d* (between plaques S and Q); *c* (between plaques Q and S); *b* (between plaques S and R); *c* (between plaques R and T); *a* (between plaques T and U); etc.

It will be observed that in the second and fourth lacing systems described, the lacing rings comprise that portion of the lacing which passes through the four pairs of registered apertures *c*, *a*, *d*, *b*, or *b*, *c*, *a*, *d*, around the points I, whereas in the third lacing system described herein, the lacing ring passes only through the three pairs of registered apertures *b*, *d*, *a*. However, in said third system, the cord 68 passes through all of the registered pairs of apertures *c* on its return run. Therefore, in each of the three lacing systems just referred to, four tiny portions of the cords 64, 68, 72 will be visible at the front of the articulated surface around the points I.

After all of the plaques in an articulated surface have been hingedly joined to one another, the surface may be employed in any well-known manner to cover a handbag or similar flexible wearing accessory. However, I prefer to mount the surface on the fabric portion of the handbag by thread loops 73 passing through the fabric and through the threading apertures 30 disposed around the mouth of said fabric portion, it being noted that with the lacing systems above described, said apertures are left clear.

This method of securing an articulated surface to a handbag lining represents a marked improvement over the methods heretofore employed. It has been the practice, generally, to bring the entire articulated surface to a sewing machine and there stitch the extending transverse laces to a lining. Such method is cumbersome, as the articulated surface is difficult to manipulate at a sewing machine. However, with my improved construction, the thread loops 73 are quickly and easily made by hand and very little sewing has to be done. Further, the threading apertures are very close to the lining so that the loops 73 are not noticeable. It will also be observed that the attachment thus obtained is highly efficient since the thread loops are anchored in the threading apertures and since the threading apertures which the loops pass through are at the corners of the plaques. This latter feature causes the plaques to be held down at the corners, whereas, up to now, plaques have been held down only centrally and the corners of the plaques became spaced from the lining, particularly at the upper ends of the sides of a bag.

In Figs. 8-12, I have shown a complete articulated surface 74 as it appears before and after application to a handbag 76. Said surface comprises a plurality of horizontal and vertical rows 20 of plaques 20 having threading apertures 30 formed therein as hereinabove described. Pursuant to a feature of the invention, I obtain an oblique articulated hollow corner in the covering for the finished bag, by substituting a triangular plaque 80 for each of the two endmost rectangular plaques in the central horizontal row 78 of plaques. The base sides 82 of said triangular plaques are the same lengths as the heights of the rectangular plaques and the slant sides of the triangular plaques are equal to the widths of the rectangular plaques. Each side of the triangular plaques 80 is provided with two threading apertures, one adjacent each corner thereof, these apertures being formed in the same manner as the apertures 30 in the rectangular plaques. The triangular plaques 80 are hingedly joined to the adjacent rectangular plaques by lacing rings which pass through either three or four pairs of registered apertures. Thus, the two left-hand rows of plaques are connected by a lacing system 79, such as shown in the pairs 66 of rows of Fig. 7, the return run of the lace being omitted. This will hingedly join the left-hand triangular plaque to the surrounding rectangular plaques. The two right-hand rows of plaques of Fig. 8 are joined by a lacing system such as shown in the pairs 56 of rows of Fig. 7.

The front or exposed face of the articulated surface 74 will, therefore, at each common point I at the bases of the triangular plaques in the left-hand or right-hand pair of vertical rows show only three tiny portions of the cord 79, as indicated in Fig. 8. However, if desired, an additional cord, such as the cord 60, may be threaded through the empty pairs of apertures.

to show four tiny portions of the threading cord at other common points, as indicated by I' of Fig. 8.

After fabrication of the flat articulated surface is completed, said surface is folded so that the central horizontal row 18 of plaques forms a flat bottom covering edge for the handbag and the plaques above and below said row form the covering for the front and back faces of the handbag, the side edges of these faces being laced together suitably by other sets of cords 77, to provide the bag with peaked (i. e., sharp or pointed) side edges 81. The bottommost plaques in the end rows are also laced by a cord 84 to the triangular plaques 80. In this manner I secure oblique hollow articulated bottom corners on the bag, which completely cover the underlying fabric and which are wholly composed of but two kinds of simply fabricated plaques. The plaques 80 may be made isosceles in shape in order to impart a symmetrical configuration to the bag.

After said surface has been so laced in the foregoing manner, it is secured by thread loops 73 to a fabric lining 86 having the shape of a bag. The upper edge of said lining carries a zipper 88 with which to close the bag in conventional fashion.

In Figs. 13-16 I have illustrated a slightly different arrangement of plaques in an articulated surface 89 which obtains another form of oblique articulated hollow bottom corner. In this articulated surface two central horizontal rows 90, 92 of plaques are provided, each of said rows having the endmost plaques omitted and isosceles plaques 94 substituted therefor. All of the plaques in said surface are laced together so as to hingedly connect the same in accordance with any one of the systems illustrated in Fig. 7. When this articulated surface is folded to cover the handbag, the two rows 90, 92 of plaques are so mutually arranged as to define a peaked bottom edge 96 for the bag, as illustrated in Fig. 14, it being observed that said rows are angularly disposed with respect to both the front and back faces of the bag. The isosceles plaques 94 are then laced together by a cord 98, which also laces together the juxtaposed side edges of the front and back faces of the handbag as illustrated in Figs. 14 and 16. In addition, said cord 98 secures the isosceles plaques to the adjacent terminal rectangular plaques in the endmost rows of plaques, as illustrated in Figs. 14 and 15. In this manner the bag is provided with peaked side edges 100 and a peaked bottom edge 96, and the bottom corners are, nevertheless, fully covered on each surface thereof by plaques, thereby protecting the underlying fabric.

In Fig. 17 there is shown an oblique, articulated hollow bottom corner 102, which can be used with a peaked bottom edge 104 and a flat side edge 106. To make this corner an isosceles plaque 108 is employed, the same having its base laced to the bottom terminal rectangular plaque 110 in the flat side edge 106 and its sloping sides laced to the terminal rectangular plaques 112 in the two rows of plaques comprising the peaked bottom edge 104.

Pursuant to my invention, triangular plaques also may be used to form oblique hollow articulated bottom corners where neither the bottom nor side edges of the handbag are peaked, this aspect of the invention being illustrated in Fig. 18. The articulated corner 114, shown therein, includes right-angles triangular plaques 116, dis-

posed at each end of certain horizontal rows in the front and back faces of an articulated surface employed to cover a handbag. These horizontal rows are those on both sides of the central horizontal row of the articulated surface from which a flat bottom of the bag is formed. The hypotenuses of the two triangular plaques at each bottom corner of the bag are laced to opposite edges of a rectangular plaque 118 which is inclined to the flat side edge 120 and flat bottom edge of the handbag. The other pair of edges of the plaque 118 are laced to the adjacent terminal rectangular plaques in the flat side and bottom edges. The remaining sides of the triangular plaques are laced to the adjacent rectangular plaques in the front and back faces of the handbag.

It will thus be seen that I have provided a plaque, articulated surface and handbag which achieve the several objects of my invention and which are well adapted to meet the conditions of practical use.

As various possible embodiments might be made of the above invention and as various changes might be made in the embodiments above set forth, it is to be understood that all matter herein described or shown in the accompanying drawings is to be interpreted as illustrative and not in a limiting sense.

Having thus described my invention I claim as new and desire to secure by Letters Patent:

1. An articulated surface consisting of a plurality of horizontally and vertically aligned rows of quadrilateral plaques, each comprising a top wall and vertical front, back and side walls, said front, back and side walls each having at least two threading apertures therein, one adjacent each end of the wall, the apertures in juxtaposed plaques being registered; said apertures each comprising a through slot in a wall opening at the bottom edge thereof, a portion of said slot adjacent its open end being closed by a ledge which circumscribes and projects outwardly from said plaque adjacent its bottom edge; adjacent plaques in pairs of adjoining rows of plaques being articulated joined by non-intersecting rows of lacing, each row of lacing passing through one after another series of pairs of registered apertures in the ends of those vertical walls of the plaques which meet at a common point so as to form a lacing ring at each such point, which hingedly joins a plaque in one row to at least another plaque in the same row as well as to at least one plaque in the adjoining row.

2. For use as an element of an articulated surface, a molded plaque consisting of a top wall having vertical walls extending rearwardly from the edges thereof, and a ledge circumscribing said plaque and projecting outwardly from adjacent the bottom edges of said vertical walls, said plaque having threading apertures in said vertical walls, each aperture comprising a through slot in such wall running upwardly from the bottom edge thereof to adjacent the top wall, a portion of the outer side of said slot adjacent its open bottom end being closed by said ledge.

3. For use as an element of an articulated surface, a molded plaque consisting of a top wall having vertical rearwardly extending peripheral walls and threading apertures in said vertical walls, each aperture comprising a through slot in the wall opening at the bottom edge thereof, a

11

portion of said slot adjacent its open end being bridged by an integral projection extending outwardly from said wall, and a plurality of means within said plaque to guide laces into said apertures, said last named means comprising a plurality of tracks, each integral with the inside of said top wall and terminating at an aperture, the end of each track remote from its associated aperture being flared.

4. For use as an element of an articulated surface, a molded plaque consisting of a top wall having vertical rearwardly extending peripheral walls and threading apertures in said vertical walls, each aperture comprising a through slot in the such wall running upwardly from the bottom edge thereof to adjacent the top wall, a portion of the outer side of said slot adjacent its open bottom end being bridged by an integral projection extending outwardly from said wall, and a through slot in said projection offset from the center of said first-named slot, said second-named slot extending up from the bottom of the element and being in communication with the threading aperture.

5. An articulated surface consisting of a plurality of transversely aligned rows of polygonal plaques having threading apertures on each side near each corner, the apertures in juxtaposed

12

plaques being registered, and means to articulatedly join adjacent plaques in pairs of adjoining rows of plaques, said means comprising non-intersecting rows of lacing, each row of lacing passing through one after another series of pairs of registered apertures at the ends of those sides of the plaques which meet at a common point so as to form a lacing ring at each such point which hingedly joins a plaque in one row to at least another plaque in the same row as well as to at least one plaque in the adjoining row.

JACOB KAPLAN.
